Patented Dec. 3, 1974

233,839

COMBINED DENTAL FORCEPS AND PROTECTIVE TONG COVER THEREFOR

Norman E. Royse, 2140 Shattuck Ave.,
Oakland, Calif. 94704

Filed Oct. 2, 1972, Ser. No. 297,765

Term of patent 14 years

Int. Cl. D24—02; D8—03
U.S. Cl. D24—1 D

FIG. 1 is a top plan view of a combined dental forceps and protective tong cover therefor with a protective tong showing my new design;

FIG. 2 is a bottom plan view thereof;

FIG. 3 is a side elevational view thereof;

FIG. 4 is a rear elevational view thereof;

FIG. 5 is a front elevational view thereof;

FIG. 6 is a top plan view of the dental forceps illustrated in FIG. 1, with the protective tong cover omitted for clarity of illustration;

FIG. 7 is a bottom plan view thereof;

FIG. 8 is a side elevational view thereof;

FIG. 9 is a rear elevational view thereof; and

FIG. 10 is a front elevational view thereof.

I claim:

The ornamental design for a combined dental forceps and protective tong cover therefor, as shown and described.
